United States Patent Office

Des. 207,278
Patented Mar. 28, 1967

207,278

TAP HOLDER

Robert E. Neeley, 1139 Mayfair Ave.,
Anaheim, Calif. 96007

Filed Nov. 22, 1965, Ser. No. 88,191

Term of patent 14 years

(Cl. D58—12.6)

FIGURE 1 is a top plan view of a tap holder in the closed position showing my new design which is capable of accepting smaller taps;

FIGURE 2 is a bottom plan view thereof;

FIGURE 3 is a top plan view thereof showing the tap holder in the open position;

FIGURE 4 is a right end elevational view thereof;

FIGURE 5 is a left end elevational view thereof;

FIGURE 6 is an enlarged detail taken along the line 6—6 of FIGURE 3;

FIGURE 7 is a bottom edge elevational view thereof, the top edge elevational view being symmetrically identical;

FIGURE 8 is a top plan view of a tap holder showing my new design in a closed position which is capable of accepting larger taps;

FIGURE 9 is a bottom plan view thereof;

FIGURE 10 is a top plan view thereof showing the tap holder in the open position;

FIGURE 11 is a right edge elevation thereof;

FIGURE 12 is a left edge elevation;

FIGURE 13 is an enlarged detail taken along the line 13—13 of FIGURE 10; and

FIGURE 14 is a bottom edge elevational view thereof, the top edge elevational view being symmetrically identical.

I claim:

The ornamental design for a tap holder, substantially as shown and described.
